UNITED STATES PATENT OFFICE.

MYER S. HESS, OF BALTIMORE, MARYLAND.

ELASTIC EDGING FOR INSOLES OF BOOTS AND SHOES.

SPECIFICATION forming part of Letters Patent No. 239,327, dated March 29, 1881.

Application filed February 2, 1881. (No model.)

To all whom it may concern:

Be it known that I, MYER S. HESS, a citizen of the United States, residing at Baltimore, in the county of Baltimore and State of Maryland, have invented certain new and useful Improvements in Elastic Edgings for Insoles of Boots and Shoes; and I do hereby declare the following to be a full, clear, and exact description of the invention, such as will 5 enable others skilled in the art to which it appertains to make and use the same, reference being had to the accompanying drawings, and to letters or figures of reference marked thereon, which form a part of this specification.

15 My invention relates to an improvement in insoles for boots and shoes, and has for its object to provide such insoles with an elastic edge against which the upper may bear without injury to the latter.

20 The ordinary leather insole, prior to my invention, is commonly chamfered a little around the edge on the lower side. After the shoe has been worn some time the edge of the insole becomes thin, sharp, and very hard, in 25 consequence of which it frequently happens that the upper is cut or breaks on a line with the edge of insole. My invention is designed to obviate this difficulty.

In the drawings hereto annexed, Figure 1 30 is a cross-section of a shoe, taken through the "ball" of the foot. Fig. 2 is an upper side view of an insole having the elastic edge attached at one side and detached from the opposite side. Fig. 3 is a cross-section of an inner sole such as is commonly employed for hand-sewed work. Fig. 4 is a cross-section of 35 an inner sole such as is commonly employed for machine-sewed work. Figs. 5 and 6 are cross-sections, on a large scale, of my edging 40 for the insoles of boots and shoes.

The letter A designates the insole of the shoe, B the upper, and C the bottom. Each edge of the insole, along that part corresponding to the tread or ball of the foot, is cut out, 45 as shown at d, on one edge in Fig. 2. The sole is prepared in this manner for both hand-sewed and machine-sewed shoes.

The elastic edging is made of any material possessing the requisite softness and elasticity, 50 preferably rubber, or some compound into

which rubber enters. I have found that rubber partially vulcanized serves for the purpose best, because its character remains unchanged. It does not soften or harden or become sticky, and is not affected by the moisture or dampness occasioned by the perspiration of the foot. The elastic edging is manufactured in strips of any convenient length, and is formed of a flat strip, which, from a thick edge on one side, tapers or bevels off to a knife-edge, e, on the other side, as shown in Fig. 6. Projecting from the thick edge, at a right angle to the flat surface, is a raised edge, F. A piece of this elastic edging is cut of proper length to fit in the "cut-out" part d of the insole, and 55 the flat surface, or that part having the beveled edge e, is attached to the lower side of the insole, by means of any suitable cement or other fastening, in such position that the raised edge F of the elastic edging may occupy the cut-out part d, which it should exactly fit. By this means it will be seen the contour or outline of the insole is restored and the leather insole is provided with a soft elastic edge. 65

70 For hand-sewed shoes the flat strip having the beveled edge is made narrower to adapt it to the peculiar bead g on the bottom of such soles. For machine-sewed shoes the flat strip is made broader, in order that the stitching 80 may pass through the flat strip. It will be understood this improvement is applicable to boots and shoes of every description.

I have shown my improvement as applied to the edge of the insole only along that part 85 corresponding to the tread of the foot, because it is at that part where most of the breaks occur in the upper; but the elastic edge may be applied to any part of the insole.

It will be noticed that when the shoe is on 90 the foot the elastic-edged insole acts as a cushion to bear on the upper, which extends under the insole.

Having described my invention, I claim and desire to secure by Letters Patent of the United States—

1. As a new article of manufacture, the edging for insoles of boots and shoes, consisting of a strip of suitable elastic material having a surface to be attached to the lower side of the 100

insole and a raised edge, F, to extend around the edge of the insole, as set forth.

2. The combination of a leather insole having each edge, along that part corresponding to the tread or ball of the foot, cut out and a strip of elastic material attached to fill the cut-out part, substantially as set forth.

In testimony whereof I affix my signature in presence of two witnesses.

MYER S. HESS.
